UNITED STATES PATENT OFFICE

156,068

DESIGN FOR A PASTRY ROLLER

Albert Brabazon, Flushing, N. Y.

Application December 2, 1946, Serial No. 135,202

Term of patent 14 years

(Cl. D44—29)

To all whom it may concern:

Be it known that I, Albert Brabazon, a citizen of the United States of America, residing at Flushing, in the county of Queens and State of New York, have invented a certain new, original, and ornamental Design for Pastry Roller, of which the following is a specification, reference being had to the accompanying drawings, forming part thereof.

Referring to the drawing,

Fig. 1 is a top plan view of a pastry roller, showing my new design.

Fig. 2 is a side view of Fig. 1.

Fig. 3 is a front view of Fig. 1.

I claim:

The ornamental design for a pastry roller, as shown.

ALBERT BRABAZON.
